Primary Examiner — Deanna L Pratt*Assistant Examiner* — Harold Blackwell, II(74) *Attorney, Agent, or Firm* — Porter Wright Morris & Arthur; Ryan Willis(57) **CLAIM**

I claim the ornamental design for a bracket, as shown and described.

DESCRIPTION

FIG. 1 is an elevated perspective view from the right front of a bracket, showing my new design, attached to a basket;
 FIG. 2 is a frontal view thereof;
 FIG. 3 is a left profile view thereof; and,
 FIG. 4 is a top view thereof.

The broken line showing of the wire basket illustrates the environment of the claimed design and forms no part thereof.
 The broken line showing of portions of the bracket illustrate portions of the bracket which form no part of the claimed design.
